CLAIM

The ornamental design of a packaging machine, as shown and described.

DESCRIPTION

FIG. 1 is a front-top-right side perspective view of a packaging machine according to my new design;

FIG. 2 is a front perspective view of the packaging machine shown in FIG. 1;

FIG. 3 is a top perspective view of the packaging machine shown in FIG. 1;

FIG. 4 is a back perspective view of the packaging machine shown in FIG. 1;

FIG. 5 is a bottom perspective view of the packaging machine shown in FIG. 1;

FIG. 6 is a right side perspective view of the packaging machine shown in FIG. 1; and,

FIG. 7 is a left side perspective view of the packaging machine shown in FIG. 1 shown with the top lid raised.

The broken lines in the drawings depict unclaimed environmental subject matter.
